L. ERIKSON

SHOW CASE REFLECTOR

Filed August 12, 1925

FIG. 1.

FIG. 2.

FIG. 3.

INVENTOR=
Leonard Erikson
By George Woodward
ATTORNEY=

UNITED STATES PATENT OFFICE.

LEONARD ERIKSON, OF MALDEN, MASSACHUSETTS.

SHOW-CASE REFLECTOR.

Application filed August 12, 1925. Serial No. 49,753.

My invention relates to show-case reflectors, and the general object thereof is to improve and simplify the construction of the same in the manner hereinafter set forth. 5
A special object of my invention is to provide a show-case reflector having a conduit for electrical conductors formed integral therewith, as for example, by reversely bending the lower end of the side member 10 of said reflector to form such conduit.

Another object of my invention is to provide means whereby the reflector may conveniently be held in position in the show case by means of a spring clip, such clip 15 having a flange formed on the lower end of its vertical side member for receiving and enclosing the aforesaid conduit, and a recess formed in its downwardly-inclined end portion for receiving a bead extending longitudinally throughout the length of the corresponding portion of the reflector.

A further object of my invention is to provide a polyangular lamp socket arranged to be received by and snugly fit within the 20 reflector, such socket having a channel co-operating with the upper surface of the aforesaid conduit.

With the aforesaid objects in view my invention comprises a trough-shaped show-case reflector having a substantially-vertical side member terminating in a conduit for electrical conductors formed by bending the lower end of said side member backward on itself, and a substantially horizontal top member terminating in a downwardly-inclined side member provided with a bead co-extensive with the length of said reflector.

My invention comprises also a resilient clip having a substantially-vertical side member and a substantially-horizontal top member, the former terminating in a flange for receiving the conduit and the latter in a bead extending beyond and adapted to snap over the downwardly inclined side member 45 of the reflector and containing a recess for receiving said longitudinally-extending bead.

My invention comprises also a polyangular lamp socket shaped to fit said reflector 50 and provided with a longitudinal channel

for receiving the upper surface of said conduit.

My invention contemplates the use of reflector members such as white opal glass, vitrified metal, glass mirrors and the like, 55 although the interior surface thereof may be plated with nickel or other suitable metal and highly polished.

When removable reflectors are employed my invention contemplates the use of retaining clips suitably shaped to hold said reflectors in position and having their ends disposed, respectively, in the depression formed by the aforesaid longitudinal bead in the surface of the downwardly-inclined side 65 member of said reflector, and in the space between the vertical side member and the reversely-bent lower end thereof.

An illustrative embodiment of my invention is shown in the drawings which accompany 70 and form a part of this specification in which:—

Figure 1 is an under plan view of a show-case reflector embodying my invention; and

Figs. 2 and 3 are transverse sections taken 75 respectively on the line 2—2 and 3—3 of Fig. 1.

In the particular drawings selected for more fully disclosing my invention 10 represents the substantially-vertical side member of my improved show-case reflector, said side member having its lower end bent back on itself to form the conduit 11 for the electrical conductors 12, 12, said conduit being shown in the present instance as substantially- 80 oblong in section, although obviously it may have any other suitable shape. The substantially-horizontal top portion 13 of the reflector terminates in a downwardly-inclined side member 14 having a bead 15 formed in the surface thereof and extending longitudinally throughout its length. In the present instance the side and top members of the reflector are joined by the portion 16 shown in the drawings as angularly 90 related thereto, although it will be understood of course that the connecting member 16 may have any suitable shape.

The reflector consisting as aforesaid of the several portions or members 10, 13, 14 and 100

16, preferably is bent into shape from a single metallic sheet, the inner surface of which may be plated and highly polished in the cheaper grade of reflector; but I prefer to employ removable reflector members such as glass mirrors and the like. The said reflectors are shown at 17 and are held in position by clips 18, one end of each of which is bent outwardly as indicated at 19 and disposed within the recess formed in the under surface of the downwardly-inclined member 14 by striking out the longitudinally-extending bead 15, while the other end 20 is arranged in the space between the reversely-bent lower end of the side member 10 and the vertical portion of said member.

It will be understood of course that said clips are formed of resilient material and are snapped into position after the reflector strips have been placed within the show-case reflector.

In Figs. 2 and 3 I show a convenient means for removably securing the reflector to the show case with which it is intended to be used, said means consisting in the present instance of a resilient clip having a substantially-vertical side member 21 terminating in an upturned flange 22 which receives and encloses the conduit 11, and a substantially-vertical top portion 23 terminating in a downwardly-inclined end portion 24 which is provided in its under side with a recess 25 for receiving the bead 15 and terminates in a bead 26 extending beyond and adapted to snap over the downwardly-inclined side member 14 of the reflector.

One or more lamp sockets 27 are employed, and in the present instance each socket is polyangular, being shaped to fit the reflector, and for the purpose of more firmly retaining the socket in the reflector, the lower lefthand corner thereof is provided with a longitudinal channel 28 for receiving the upper surface of the conduit 11, a screw 29 or other suitable securing means being employed to fasten said socket to the reflector.

Preferably a strip of mica 30, or other suitable insulator is interposed between the recessed portion 31 of the socket which contains the lamp terminals 32 and the reflector, and the upper wall of the conduit 11 which is opposite the recessed portion 31 of the socket is cut away as indicated at 33 for the passage of the conductors 12, 12 from the lamp terminals to said conduit.

Having thus described an illustrative embodiment of my invention without however limiting the same thereto, what I claim and desire to secure by Letters Patent is:—

1. A trough-shaped show-case reflector comprising a substantially-vertical side member and a substantially-horizontal top member, said top member terminating in a downwardly-inclined side member having a

longitudinally-extending bead throughout its length, and said side member having its lower end reversely bent to form a conduit for electrical conductors, in combination with a resilient clip having a substantially vertical side member provided with means for supporting said conduit, and a substantially-horizontal top member terminating in a downwardly inclined end portion having a recess for receiving said bead formed in said reflector.

2. A trough-shaped show-case reflector comprising a substantially-vertical side member and a substantially-horizontal top member, said top member terminating in a downwardly-inclined side member, and said side member having its lower end reversely bent to form a conduit for electrical conductors in combination with a resilient clip having a substantially-vertical side member provided with means for supporting said conduit and a substantially-horizontal top member terminating in a downwardly inclined end portion and having a bead extending beyond and adapted to snap over the downwardly inclined side member of said reflector.

3. A trough-shaped show-case reflector comprising a substantially-vertical side member and a substantially-horizontal top member, said top member terminating in a downwardly-inclined side member having a longitudinally-extending bead throughout its length, and said side member having its lower end reversely bent to form a conduit for electrical conductors, in combination with a resilient clip having a substantially-vertical side member terminating in an upturned flange receiving and enclosing said conduit, and a substantially-horizontal top member terminating in a downwardly inclined end portion having a recess for receiving said bead formed in said reflector and provided with a terminal bead extending beyond and adapted to snap over the downwardly inclined side member of said reflector.

4. A trough-shaped show-case reflector comprising a substantially-vertical side member and a substantially-horizontal top member, the lower end of said side member being reversely bent to form a conduit for electrical conductors, and a polyangular lamp socket shaped to fit said reflector, said socket having a longitudinal channel for receiving the upper surface of said conduit.

5. A trough-shaped show-case reflector comprising a substantially-vertical side member and a substantially-horizontal top member, said top member having a longitudinally-extending bead throughout its length, and said side member having its lower end reversely bent to form a conduit for electrical conductors, reflector members arranged on the interior surfaces of said

reflector, and a clip for retaining said reflector members in position, said clip having one end disposed in the depression formed in the under surface of said downwardly inclined side member by said bead and the other end thereof disposed in the space between the reversely bent lower end of said

side member and the vertical portion of said side member.

In testimony whereof, I have hereunto 10
subscribed my name this 11th day of August,
1925.

LEONARD ERIKSON.
